(57) **CLAIM**

The ornamental design for a hair extension comprising tinsel strands, as shown and described.

DESCRIPTION

FIG. 1 is a front elevational view of a hair extension comprising tinsel strands;

FIG. 2 is a rear elevational view thereof;

FIG. 3 is a right front perspective view thereof,

FIG. 4 is an enlarged front elevational view of the top portion thereof;

FIG. 5 is an enlarged right side elevational view of the top portion, the left side elevational view being a mirror image thereof;

FIG. 6 is an enlarged top plan view of the top portion thereof;

FIG. 7 is a left front perspective view in an environment of use; and,

FIG. 8 is a front elevational view in another environment of use.

The broken lines in FIGS. 7 and 8 illustrate an environment for a hair extension comprising tinsel strands that form no part of the claimed design.

1 Claim, 8 Drawing Sheets
